UNITED STATES PATENT OFFICE

JAMES R. CARDWELL, OF CHICAGO, ILLINOIS, ASSIGNOR TO CARDWELL WESTINGHOUSE COMPANY, A CORPORATION OF DELAWARE

DRAFT GEAR

Application filed January 13, 1930. Serial No. 420,688.

This invention relates to draft gears for railway cars and more particularly to draft gears of the friction type.

One of the objects of the invention is the provision of new and improved means for automatically compensating for wear of the friction elements in a draft gear whereby the proportionate amount of force applied to the gear that is transferred to the plates will remain constant irrespective of said wear.

Another object of the invention is the provision of new and improved means for releasing the parts of the draft gear and returning the same to normal position after compression.

A still further object of the invention is the provision of new and improved pressure members for forcing the frictional elements into contact during compression of the gear.

Other objects of the invention are the provision of a new and improved draft gear that is simple in construction, cheap to manufacture, easily assembled, efficient and reliable in operation, and one in which the frictional resistance to compression will not be affected by the wear of the friction elements.

Other and further objects and advantages of the invention will appear from the following description taken in connection with the accompanying drawings, in which

Fig. 1 is a plan view of the center sills of a railway car showing the invention in position therein, with parts in section and parts broken away;

Fig. 2 is a vertical section of the gear;

Fig. 3 is a view similar to Fig. 1 with the parts in collapsed position;

Fig. 4 is a section on line 4—4 of Fig. 3;

Fig. 5 is a perspective view of one of the friction plates;

Fig. 6 is a perspective view of one of the spring seats;

Fig. 7 is a perspective view of one of the shoe engaging plates;

Fig. 8 is a perspective view of one of the fulcrum blocks;

Fig. 9 is a diagrammatic view of the cam blocks in assembled relation; and

Fig. 10, 11 and 12 are diagrammatic views

employed in the mathematical demonstration of the curves employed.

On the drawings, the reference character 10a designates the center sills of a railway car each of which is provided with the draft lug 11a and the buffer lug 12a.

Mounted between said lugs is the draft gear which comprises a pair of casings or sleeves 13 and 14 within which is located two oppositely arranged groups of friction plates. Each group comprises two sets of intercalated plates 15 and 16 overlapping at their inner ends.

Follower blocks 17 and 18 are inserted between the lugs and draft gear. A draft yoke 19 secured to the coupler butt 21 embraces the gear as is usual in such constructions.

Suitable means are provided for forcing the friction plates into contact with each other during the compression of the gear. In the form of the device selected to illustrate one embodiment of the invention cam members are employed for this purpose. Since the arrangement at the ends of the gear is similar only one end need be described. Friction shoes 22 and 23 are arranged in frictional contact with the two groups of friction plates. These shoes are adapted to be forced outwardly against the friction plates by the cam blocks 24 and 25 which engage suitable curved recesses 26 in said shoes. The opposite ends of the blocks are provided with curved toes or projections 27 for engaging the fulcrum block 29. The block 29 may, if desired, be provided with inclined faces 28 although this is not necessary. The blocks 24 and 25 are also provided with intermediate curved surfaces 31 which are adapted to engage each other as at 32.

If the force for compressing the gear be considered as always being applied along the center line of the gear, see Fig. 9, it can be readily proved that the curves of the contacting faces 31 of the cams 24 and 25 will be the same and both will be logarithmic spirals having the line 20, 20 as their common tangent, for "the chief property of this curve is that the tangent at any point always makes the same angle with its radius." If now we so construct the cams that the lines 32, 33 and

- 32, 34 are the radius vectors of these curves, it is evident that since the angles 20, 32, 33 and 20, 32, 34 or the angle 33, 32, 34 which, for convenience of description, will be termed the pressure angle, remain constant, the thrust on the shoes for any given force applied along the line 20, 20 will remain constant irrespective of the amount of wear on the friction plates.
- 10 In actual practice, however, the force is not applied along the line 20, 20 but is applied at each side of said line, consequently the actual result will differ somewhat from the theoretical one unless provision be made 15 for compensating for this application of the force. This may be accomplished by the use of the proper curves at 27. The equation for these curves will vary depending on the angle of the faces 28 which may vary from zero to 20 any suitable angle, as will presently appear.

The following is a mathematical discussion of the problems involved and in which the equations for the different curves are derived.

- 25 Referring now to the diagrammatic view, shown in Figs. 10, 11 and 12, the letters A, A', are employed to designate a set of cam blocks B a member through which the force is applied, C the member resisting such force, and 30 D the member for resisting the side thrusts of the members A, A'.

The boundary curves of the movable blocks

As indicated, a force $2F$ acts through the 35 rigid block B on A and A'. The contact of B with A and with A', for the purpose of this discussion, is regarded as being frictionless. At points 2 and 3 the reaction must be normal to the boundaries of A and A' respectively. This determines the resultant R acting at 2, as shown. The blocks A and A' are in contact (frictionless) at the point 4; their reactions T are normal to the boundary curve at 4. The forces R and T may be combined at 45 the point 5 of intersection of the normals at 2 and 4. The magnitude of T is determined from the fact that when the block A is in equilibrium the resultant W of T and R must have the direction from 5 to the point 11 of intersection of the lines of action of the forces acting at points 7 and 9. The force at 9 must have the magnitude F , to balance the only other external force applied to A (considering those forces to be F and S at point 2) 50 which have components in the direction of F at 2.

Calling the force acting at the point 7, which is of prime interest in our problem, X, we combine X and F at the point 11. The 60 resultant W must have the direction from point 11 toward the point 5, which determines the magnitude of X.

Thus the total reaction of the rigid block C is $2F$ on the two blocks A and A', while 65 the reaction of the wall D is X.

Let t be the angle from the line joining points 11 and 12, which we shall designate the line (11, 12), to the line (11, 5). Then the ratio of X to F is $\cot t$.

$$(1) \quad X/F = \cot t.$$

70

We state now our main problem as follows.

Problem.—A variable force $2F$ is applied at B causing small translations and partial rotations of the blocks A and A', displacing 75 blocks B, C and D, changing the points of contact 2, 4, 7 and 9, and changing the magnitudes of S, R, T, W and X. It is required to find the shape of the boundary curves of A in the neighborhoods of 2, 4, 7 and 9 such 80 that for small translations and rotations the ratio of X to F is constant.

In view of Equation (1) this problem becomes a purely geometric one which may be stated as follows.

85

Equivalent geometric problem.—Find shapes of curves in the vicinity of 2, 4, 7 and 9 such that for small translations and rotations of A, in which the point of contact 4 moves along the line l , the line (11, 5) remains parallel to its original position, where 11 is the point of intersection of the normals at 7 and 9, and 5 of the normals at 2 and 4.

90

In solving this geometric problem we need consider only one of the two symmetrically shaped blocks A and A', and the forces no longer need to be considered.

95

In Fig. 11 is represented block A before and after it has been moved. The new positions of points of contact with its boundaries 100 are indicated by accents; thus 2' is the new point of contact of the block B with A. The boundary curves were not properly drawn since the line (11', 5') is not parallel to the line (11, 5) as it must be for a solution of our 105 problem.

Let us take the boundary curve in the vicinity of points 7 and 9, a circle with center at point 11. Then the point 11' is the same point in the block as is the point 11. (Note 110 that 5' and 5 cannot, therefore, be the same point in the block A, since there has been a rotation.)

Let us now translate the part of the figure carrying accented points so that point 11' 115 comes into coincidence with point 11. Such a translation does not change the angles between lines. The line (11', 5') in its new position will be parallel to or coincident with (11, 5), if and only if it was either parallel to or coincident with it before the translation. This translation leads from Fig. 11 to Fig. 12 (the drawing is diagrammatic only).

For the sake of simplicity, we shall determine the curves so that the line (11', 4') is 120 parallel to (11, 4) in Fig. 11 which requires the lines to coincide in Fig. 12. Also we shall make the line (2, 5) perpendicular to (11, 5).

In Fig. 12 a curve passing through 130

points 2, 2'', 4'', 4 is rotated about the fixed point 11, through an angle α , coming into a position passing through points 2', 4'. In the figure α is a negative angle, θ is positive.

5 If the line (11, 5) is used as a polar axis for polar coordinates, then the point (r, θ) goes into a point $(r, \theta+\alpha)$ by the rotation. These conditions must hold for all small values of α

- (1) The tangents at 2 and 2' are parallel.
- (2) The tangents at 4 and 4' are parallel.
- (3) The point 4' lies on the line (11, 4).
- (4) The point (5') lies on the line (11, 5).

In the following discussion we shall use the following.

15 Theorem I.—The angle made by the radius vector to a point on a curve with the tangent at that point is not changed when the figure is rotated about the pole.

20 The curve through point 4

Consider now the curve through the point 4 (a_0, ϕ_0) . Let 4'' (r, ϕ) be a point near 4, and let the angle made with the radius vector by the tangent at 4 be ψ_0 and at 4'' be ψ . Then from differential calculus $\tan \psi = r \frac{d\phi}{dr}$

30 When 4'' is brought into coincidence with 4' by rotation of the figure it is seen that, by conditions (2) and Theorem I, $\psi = \psi_0$.

Hence

$$r \frac{d\phi}{dr}$$

is constant; call it $1/k$; that is,

$$r \frac{d\phi}{dr} = \frac{1}{k}$$

40 The integral of this differential equation which satisfies the conditions, when $\phi = \phi_0$, and $r = a_0$, is

45 (2) $r = a_0 e^{k(\phi - \phi_0)}$, or $\log r/a_0 = k(\phi - \phi_0)$.

This curve is called a logarithmic spiral. It is a necessary and sufficient form for the curve through (4) satisfying conditions which we have imposed.

50 Since $\tan \psi_0 = 1/k$, we see that, in Fig. 12 (2') $k = \tan \beta$.

The curve through point 2

55 Consider now the curve through the point 2 (r_0, θ_0) . A point P (r, θ) near 2 goes, on rotation of the figure through a small angle α into a point 2' $(r, \theta+\alpha)$, which is such that

(1) The tangent at 2' is parallel to the tangent at 2;

(2) The normal at 2' intersects the normal at 4' in a point 5' which lies on the line (11, 5).

Let ψ be the angle made by the tangent with

65 the radius vector at P, and ψ' be that angle

at 2'. Since the tangent line at 2' is parallel to the polar axis we see that $\psi = \pi - (\theta + \alpha)$.

Since the configuration at 2' comes from that at P by rotating that latter about the pole, it follows that $\psi = \pi - (\theta + \alpha)$.

By differential calculus

$$\tan \psi = r \frac{d\theta}{dr}$$

Hence

$$(3) r \frac{d\theta}{dr} = -\tan(\theta + \alpha)$$

Let the polar coordinates of 5 and 5' be (x, ϕ) and (x', ϕ) respectively. Since the lines (5, 4) and (5', 4') are parallel, it follows that

$$\frac{x}{x'} = \frac{a_0}{a}$$

At 4'' we have $r = a$, $\phi = \phi_0 - \alpha$. Substitute these values in (2), the equation of the curve through 4''; we find

$$a = a_0 e^{-k\alpha}$$

Hence

$$\frac{x}{x'} = e^{-k\alpha}$$

We have also, since the line (5', 2') is perpendicular to the line (11, 5),

$$x' = r \cos(\theta + \alpha)$$

Hence

$$(4) x = e^{-k\alpha} r \cos(\theta + \alpha)$$

The number x is expressible in terms of coordinates of the given point 2; thus

$$x = r_0 \cos \theta_0$$

Thus (4) defines α as a function of r , θ and constants x , k .

Hence the curve through 2 is the solution of (3) where α is the function defined implicitly by (4).

From the theory of implicit functions it follows, after some calculations, that Equation (4) defines α as a single valued and analytic function of r , θ in the vicinity of $r = r_0$, $\theta = \theta_0$, $\alpha = \alpha_0$ if and only if $\theta_0 = -\beta$.

Parametric equations of the curve through 2

We wish to solve the equations

$$(3) r \frac{d\theta}{dr} = -\tan(\theta + \alpha),$$

$$(4) x = e^{-k\alpha} r \cos(\theta + \alpha)$$

Here x and k are constants, and r , θ and α are variables, α being small. We have the boundary conditions,

$$(5) \alpha = 0, r = r_0, \theta = \theta_0,$$

with the relation $x = r_0 \cos \theta_0$.

Since α is small we may use it as a parameter in terms of which to express r and θ by

use of power series. From (3) and (4) we have we have

$$(6) \quad xe^{k\alpha} d\theta = -\sin(\theta + \alpha) dr,$$

$$(7) \quad xe^{k\alpha} = r \cos(\theta + \alpha).$$

Let

$$(8) \quad \theta = \theta_0 + \theta_1 \alpha + \theta_2 \alpha^2 + \dots,$$

$$r = r_0 + r_1 \alpha + r_2 \alpha^2 + \dots.$$

10 The conditions (5) are satisfied. Then we have

$$(9) \quad e^{k\alpha} = 1 + k\alpha + \frac{k^2 \alpha^2}{2!} + \frac{k^3 \alpha^3}{3!} + \dots,$$

$$15 \quad d\theta = d\alpha [\theta_1 + 2\theta_2 \alpha + 3\theta_3 \alpha^2 + \dots],$$

And since

$$20 \quad \text{Sin } (\theta + \alpha) = \sin(\theta_0 + \alpha \rho)$$

$$= \sin \theta_0 \cos \alpha \rho + \cos \theta_0 \sin \alpha \rho$$

$$(12) \quad xe^{k\alpha} d\theta = x d\alpha \left[\theta_1 + (\theta_1 k + 2\theta_2) \alpha + \left(\frac{\theta_1 k^2}{2!} + 2\theta_2 k + 3\theta_3 \right) \alpha^2 + \dots \right]$$

Moreover For the right member of (6) we get, from (10) and (11),

$$(13) \quad -\sin(\theta + \alpha) dr = -d\alpha \left[r_1 \sin \theta_0 + (2r_2 \sin \theta_0 + r_1 \cos \theta_0 (1 + \theta_1)) \alpha \right.$$

$$25 \quad \left. + \left\{ (\theta_2 \cos \theta_0 - \sin \theta_0 \frac{(1 + \theta_1)^2}{2!}) r_1 + 2r_2 \cos \theta_0 (1 + \theta_1) + 3r_3 \sin \theta_0 \right\} \alpha^2 + \dots \right]$$

$$\text{Cos } (\theta + \alpha) = \cos(\theta_0 + \alpha \rho)$$

$$= \cos \theta_0 \cos \alpha \rho - \sin \theta_0 \sin \alpha \rho,$$

20

On equating like powers of α in the right members of Equations (12) and (13) we have

$$(14) \quad x\theta_1 + r_1 \sin \theta_0 = 0$$

$$2x\theta_2 + 2r_2 \sin \theta_0 = -kx\theta_1 - r_1 \cos \theta_0 (1 + \theta_1)$$

$$3x\theta_3 + 3r_3 \sin \theta_0 = -2kx\theta_2 - \frac{\theta_1 x k^2}{2!} - 2r_2 \cos \theta_0 (1 + \theta_1) - \theta_2 \cos \theta_0 + \sin \theta_0 \frac{(1 + \theta_1)^2}{2!}$$

35 where

$$\rho = (1 + \theta_1) + \theta_2 \alpha + \theta_3 \alpha^2 + \dots,$$

The left member of (7) may be expressed as a power series in α by multiplying the right member of (9) by x . For the right member of (7) we find from (8) and (10)

$$40 \quad r \cos(\theta + \alpha) = r_0 \cos \theta_0 + (r_1 \cos \theta_0 - r_0 \sin \theta_0 (1 + \theta_1)) \alpha$$

$$+ \left\{ r_2 \cos \theta_0 - r_1 \sin \theta_0 (1 + \theta_1) + r_0 \left[-\frac{(1 + \theta_1)^2 \cos \theta_0}{2!} - \theta_2 \sin \theta_0 \right] \right\} \alpha^2$$

$$45 \quad + \left\{ r_3 \cos \theta_0 - r_2 \sin \theta_0 (1 + \theta_1) + r_1 \left[-\frac{(1 + \theta_1)^2 \cos \theta_0}{2!} - \theta_2 \sin \theta_0 \right] \right\} \alpha^3$$

$$+ r_0 \left[\dots \right] + \dots$$

50 and

$$\cos \alpha \rho = 1 - \frac{(\alpha \rho)^2}{2!} + \frac{(\alpha \rho)^4}{4!} - \dots$$

$$55 \quad = 1 - \frac{(1 + \theta_1)^2}{2!} \alpha^2 - \frac{2\theta_2(1 + \theta_1)}{2!} \alpha^3 + \dots -$$

Hence on equating like powers of α in the two members of (7) we obtain

$$(15) \quad x = r_0 \cos \theta_0,$$

$$r_0 \sin \theta_0 \theta_1 - r_1 \cos \theta_0 = -xk - r_0 \sin \theta_0, \quad 120$$

$$r_0 \sin \theta_0 \theta_2 - r_2 \cos \theta_0 = -\frac{xk^2}{2} - r_1 \sin \theta_0 (1 + \theta_1) + r_0 \frac{(1 + \theta_1)^2 \cos \theta_0}{2!}$$

$$60 \quad \sin \alpha \rho = \alpha \rho - \frac{(\alpha \rho)^3}{3!} + \frac{(\alpha \rho)^5}{5!} \dots$$

$$= (1 + \theta_1) \alpha + \theta_2 \alpha^2 + \frac{6\theta_3 - (1 + \theta_1)^3}{3!} \alpha^3 + \dots -$$

65

The first equation of (15) is satisfied, from the definition of x . The first equation of (14) and the second of (15) serve to determine

$$(16) \quad r_1, \theta_1; \text{ we have } x\theta_1 + r_1 \sin \theta_0 = 0, \\ r_0 \sin \theta_0 \theta_1 - r_1 \cos \theta_0 = -xk - r_0 \sin \theta_0, \quad 130$$

whence, since $x = r_o \cos \theta_o$,

$$(17) \quad \begin{aligned} 1 &= \frac{0, + \sin \theta_o}{-kr_o \cos \theta_o - r_o \sin \theta_o, -\cos \theta_o} \\ 5 &= \frac{r_o \cos \theta_o, + \sin \theta_o}{r_o \sin \theta_o, -\cos \theta_o} \\ &= + \frac{r_o(k \sin \theta_o \cos \theta_o + \sin^2 \theta_o)}{-r_o} \end{aligned}$$

It appears that calculations will be simplified if we wrote

$$(18) \quad x = r_o \cos \theta_o, y = r_o \sin \theta_o, \\ r = r_o r', r' = 1 + r_1' \alpha + r_2' \alpha^2 + \dots, \\ 15 \quad r_1 = r_o r_1', r_2 = r_o r_2'.$$

Equations (16) become

$$(19) \quad x\theta_1 + y r_1' = 0, \\ y\theta_1 - x r_1' = -kx - y.$$

The solution of these equations is found to be

$$(20) \quad \theta_1 = -\frac{y(kx + y)}{x^2 + y^2}, \quad r_1' = \frac{x(kx + y)}{x^2 + y^2}.$$

To find θ_2, r_2' we solve simultaneously the second of Equations (14) and the third of Equations (15). After a long calculation we obtain

$$(21) \quad \begin{aligned} 25 \quad \theta_2 &= -\frac{x}{2(x^2 + y^2)^3} \left\{ kx^5 + (2 - k)x^4y - (1 + k^2)x^3y^2 + (2 - k + k^2)x^2y^3 \right. \\ &\quad \left. - (1 + 2k)xy^4 + k^2y^5 \right\}, \\ r_2' &= +\frac{x}{2(x^2 + y^2)^3} \left\{ (1 + k^2)x^5 - kx^4y + (1 - k + 2k^2)x^3y^2 \right. \\ &\quad \left. + (1 - 2k + k^2)x^2y^3 + (k + k^2)xy^4 + y^5 \right\}. \end{aligned}$$

The method we have followed can be used to determine as many of the constants θ_i, r_i as may be desired. We thus have the parametric equations of the desired curve:

$$(22) \quad \begin{aligned} 40 \quad r &= r_o(1 + r_1' \alpha + r_2' \alpha^2 + \dots), \\ \theta &= \theta_o + \theta_1 \alpha + \theta_2 \alpha^2 + \dots \end{aligned}$$

The equations are worked out in such a form, containing the parameters x, y and k , that one may choose (Fig. 12) point 2 and the direction of the tangent at 2 arbitrarily with respect to point 11 and line l , and then find the curves in the vicinity of points 4 and 2 to meet the conditions of the problem.

Suitable means are provided for resisting the inward movement of the shoes 22 and 23. As shown, the shoes are provided with shoulders 35 against which shoe engaging plates 36 are adapted to engage. A resilient member, as the spring 37, is interposed between these plates and is adapted to resist the movements of the shoes at one end of the gear toward those at the other.

The fulcrum blocks 29 normally extend outwardly beyond the ends of the friction plates, whereby during the initial compression of the gear the block 29 will move inwardly, thereby forcing the shoes 22 and 23 laterally into frictional engagement with the friction plates before the ends of the same engage the follower blocks.

Resilient means such as the spring 38 is employed for yieldingly resisting the inward movement of the fulcrum blocks 29 and the collapsing of the gear, in a manner that will now be described. The fulcrum blocks 29 are each provided with inwardly extending arms 39 which are adapted to embrace the plate 36 between the laterally extending lugs 42. The ends of the spring 38 engage spring seats or plates 41 which in turn engage the inner ends of the arms 39 of the fulcrum blocks 29. The plates 41 are each provided with inwardly extending projections 44 for positioning the spring 38. The plates 41 are each provided with an axial opening through which the spring 37, which is preferably arranged within the spring 38, extends and is held in position in the gear.

Suitable means are provided for returning the parts to normal position after compression. The springs 37 and 38 are preferably utilized for this purpose. Retracting bars 45 are adapted to engage notches 46 in the outer ends of the plates 15 and 16 at each edge thereof. The inner ends of the plates are reduced as at 47 for engaging between the bars 45 of the opposed set of plates. The projections or lugs 42 on the shoe engaging

plates are adapted to engage the retracting bars at each side of the gear for retracting the friction plates.

Lugs 48 on the sleeves 13 and 14 are adapted to be engaged by the retracting bars for returning the sleeves to normal position along with the other parts of the gear. The lugs 48 on the inner surface of the sleeves serve also as means for positioning the fulcrum blocks 29.

If desired, means may be provided for holding the parts in assembled position for shipment, handling and the like. As shown, a cylinder 51 having removable caps which carry bolts 52, is mounted within the springs axially of the gear, with the bolts 52 in engagement with a depressed portion 53 in each block 29, see Figs. 1 and 2. The cam blocks 22 and 23 are provided with suitable recesses for accommodating the bolts and the depressed portions 53 in the fulcrum blocks.

In the operation of the device, when force is applied tending to compress the gear, the followers 17 and 18 will first engage the fulcrum blocks 29, forcing the same inward against the tension of the spring 38, and at the same time, through the action of the cam blocks, the shoes are forced inwardly against the spring 37 and laterally outwardly, thus creating a transverse pressure on the friction plates. Further movement results in

the followers engaging the sleeves and friction plates to force the same inwardly while in frictional contact with each other.

When compression is removed the spring 38 will move the fulcrum blocks 29 outwardly, thus relieving the pressure on the friction plates. The spring 37 will move the plate 36 outwardly, and with it the retracting bars 45, and through them the friction plates and sleeves. In actual practice, the spring seat 41 will engage the plate 36 and the combined action of the springs 37 and 38 will promptly move the parts to normal position. By means of this arrangement, the release of the transverse pressure on the friction plates is assured immediately after compression, and the prompt return of the parts of the gear to normal position is also assured.

This is a continuation in part of my application Serial No. 1,320 filed January 8, 1925, for patent on draft gear.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

20 I claim as my invention:

1. In a draft gear, a group of friction elements, means including a pair of friction sleeves open at each end for containing said elements, certain of said elements being movable with one of said sleeves, and certain of said elements being movable with the other sleeve, and means comprising toggle blocks normally extending beyond the outer ends of said sleeves for creating transverse pressure on said elements during compression of said gear, and means for returning the parts to normal position after compression.

2. In a draft gear, a pair of open-ended sleeves, a group of intercalated friction plates within said sleeves, means including rotatable cam and fulcrum blocks for creating transverse pressure on said plates during compression of said gear, said fulcrum blocks normally extending beyond the ends of said sleeves, and means to return the parts to normal position after compression.

3. In a draft gear, a pair of friction sleeves, friction elements in said sleeves, means including rotatable cam blocks for creating transverse pressure on said elements during compression of said gear, resilient means which, during its initial return movement, will release said cam blocks and during its final movement will exert pressure to return the parts to normal position.

4. In a friction gear, a pair of sleeves, intercalated friction plates within said sleeves, means including rotatable cam blocks for creating transverse pressure on said plates, fulcrum blocks for engaging said cam blocks,

and resilient means for engaging said fulcrum blocks for releasing the lateral pressure on said plates after compression.

5. In a draft gear, a pair of sleeves, a group of friction elements extending into both of said sleeves, rotatable cam blocks for engaging said elements, fulcrum blocks for engaging said cam blocks for creating transverse pressure on said elements during compression of said gear, and resilient means for resisting the inward movement of said fulcrum blocks and cam blocks and for returning the parts to normal position after compression.

6. A draft gear comprising a pair of sleeves, a group of intercalated plates frictionally engaging each other, within said sleeves, certain of said plates being movable with one of said sleeves and the remainder with the other sleeve, friction shoes in engagement with said group of plates, rotatable cam members engaging said shoes, and fulcrum blocks for creating transverse pressure on said plates on compression of said gear, plates in engagement with said shoes, a spring between said plates, spring seats inwardly of said plates in engagement with said fulcrum blocks, and a spring engaging said seats.

7. In a draft gear, a pair of casings, a group of two sets of friction elements within said casing for frictionally engaging each other, one group of said plates being movable with one of said sleeves and the other with the other sleeve, means including fulcrum blocks, rotatable cam members and friction shoes for creating transverse pressure on said elements at opposite ends thereof during compression of said gear, a spring for resisting the inward movement of said shoes, said spring on its initial release movement forcing said blocks outwardly and on its final movement exerting pressure to return said elements to normal position.

8. In a draft gear, a pair of sleeves, a group of friction elements including friction shoes mounted within said sleeves, means including a fulcrum block and rotatable cam members for creating transverse pressure on said elements during compression of said gear, for causing them to frictionally engage each other, certain of said elements being movable with one of said sleeves and certain of said elements being movable with the other sleeve, a spring for resisting the inward movement of said blocks, and a spring for resisting the inward movement of said shoes, said first-named spring forcing said blocks outwardly during its initial release movement and on its final movement cooperating with said second-named spring for returning said elements to normal position.

9. In a draft gear, a group of intercalated plates, means to limit the lateral movement of said plates, friction shoes in engagement

- with said group of plates, plates engaging said shoes, a spring between said plates, means comprising rotatable cam and fulcrum blocks for creating transverse pressure 5 on said shoes during compression of said gear, and spring seats in engagement with said fulcrum blocks, said seats being adapted to engage said shoe engaging plates for returning the parts to normal position after compression.
10. In a draft gear, a group of intercalated friction plates, a pair of casing members for containing said plates, means including rotatable cam members for creating transverse 15 pressure on said plates at each end of said gear on compression thereof, and means for returning the parts to normal position after compression.
11. A draft gear comprising a plurality 20 of relatively movable intercalated friction plates, casings for containing said plates, means including intercontacting toggle blocks for creating transverse pressure on said plates during compression of said gear, 25 the contacting faces of said blocks being so curved that the point of contact will advance as the outer ends of said blocks move outwardly, and means for returning said parts to normal position after compression.
12. In a draft gear comprising a group of 30 intercalated friction plates, a pair of retaining members for containing said plates, means including toggle members and fulcrum blocks for creating transverse pressure on 35 said plates, and spring means engaging said fulcrum blocks for releasing the same after compression.
13. In combination, a pair of friction sleeves, a group of plates within said 40 sleeves at each side of the axis thereof, a fulcrum block at each end of said gear and normally extending outwardly beyond the ends thereof, a pair of rotatable cam members in engagement with said blocks at each 45 end of said gear, and means for yieldingly resisting the inward movement of said cam members during compression of said gear for creating transverse pressure on said plates, and resilient means for returning said 50 blocks to normal position after compression.
14. A draft gear comprising a pair of open-ended sleeve members, friction elements within said sleeve members, certain of said elements being movable with one of said sleeves 55 and the remaining elements with the other sleeve, means including toggle members for creating transverse pressure on said elements for forcing the same outwardly against said sleeve members during compression of said 60 gear for resisting said compression, and means to return the parts to normal position after compression.
15. In a draft gear, a group of friction elements including friction shoes adapted to 65 slide longitudinally of said gear, resilient
- means for resisting inward movement of said shoes, means including toggle members engaging said shoes for creating transverse pressure on said friction elements during compression of said gear, means for resisting said transverse pressure, and spring means for yieldingly resisting inward movement of said shoe engaging members, said spring means forcing said members outwardly during its initial release movement and on its 70 final movement cooperating with said resilient means to return the parts to normal position.
16. In a draft gear, a group of relatively movable friction elements, means for limiting the lateral movement of said elements in one direction, and means for creating lateral pressure on said elements during the compression of said gear, said means including cam members having their contacting faces 80 of such curvature that the lateral resultant of a force applied to the ends of said gear will remain constant irrespective of the wear on said elements, and means for resisting the compression of said gear and for returning 85 the parts to normal position after compression.
17. In a draft gear, a group of relatively movable friction elements, means for limiting the lateral movement of said elements 90 in one direction, means for yieldingly resisting the longitudinal inward movement of said elements and for creating lateral pressure thereon during the compression of said gear, said means comprising toggle members 95 having their contacting surfaces in the form of logarithmic spirals, and resilient means for returning the parts to normal position after compression.
- In testimony whereof I affix my signature. 105
